UNITED STATES PATENT OFFICE.

BYRON B. SWITZER, OF CHICAGO, ILLINOIS.

AUTOMOBILE.

No. 832,636.

Specification of Letters Patent.

Patented Oct. 9, 1906.

Application filed November 15, 1905. Serial No. 287,800.

To all whom it may concern:

Be it known that I, BYRON B. SWITZER, a citizen of the United States, residing at Chicago, in the county of Cook and State of Illinois, have invented certain new and useful Improvements in Automobiles, of which the following is a specification.

My invention relates to automobiles, and has for its object to provide a new and improved device of this character in which the various operations of starting and stopping may be effected with greater facility and without the use of complicated mechanism.

The invention consists in the construction described in the accompanying specification and set forth in the claims.

In the drawings, Figure 1 is a side elevation of an automobile containing my invention. Fig. 2 is a similar view showing the essential features of my invention.

In the drawings, *a* represents an automobile of conventional form having a metal frame *b*, as is usual and well known.

c represents the rear or driving wheel, and *d* the usual front wheel. The rear or driving wheel *d* is mounted upon an axle *g*. This axle is secured to the upright end of a drop axle-bar *e*, which is mounted in bearings 2 so as to rock therein. The rim *h* of the rear or driving wheel is grooved for a purpose presently described. It will be noticed that the axle *g* is mounted upon the upturned portion *f* of the axle-bar a short distance below the upper end of such upturned portion and that this upper end *k* is connected by a connecting-rod *p* to an operating-lever *n*, fulcrumed at *o* in the frame of the machine.

q represents a semicircular rack-bar having teeth which are engaged by a dog (not shown) mounted upon the operating-lever *n*. A pivoted operating-handle *r* is connected to this dog, as will be readily understood.

Mounted in the frame of the machine adjacent the rear wheel is an operating-pulley *l*, grooved on its circumference. This pulley is suitably connected to a motor in any well-known manner. The particular type of motor, however, forms no part of my invention, and therefore has not been illustrated. The pulley *l* has also a reduced portion *l'*, the circumference of which is plain. A rope or other flexible connection *m* connects the pulley *l* with the rear wheel, as shown. Mounted in the side bar of the frame is a brake-bar *t*, having at the end adjacent the driving-wheel a brake-shoe *s*. This brake-bar is normally

urged toward the driving-wheel by a spring *u* at the opposite end thereof. A latch or detent *v*, connected to a spring-pressed foot-lever *w* on the frame of the machine, serves to hold the brake-bar against movement.

It will be seen that when the operating-lever *r* is pushed forward toward the front of the carriage it will, through the connecting-rod *p*, cause the drop axle-bar to swing backward away from the motor. This will result in the tightening of the rope or flexible connection *m*. Consequently the power of the motor will be transmitted to the rear driving-wheel and the carriage will move forward. When the operating-lever is in its middle or neutral position, the driving-wheel will be in the position shown in Fig. 1 and the flexible connection will be loose, so that the movement of the motor will not be transmitted to the driving-wheel. The carriage will consequently remain standing. When it is desired to reverse the movement of the carriage and run backward, the operating-lever is pulled toward the rear of the carriage, as indicated in Fig. 2. This will swing the axle-bars forward. Consequently the driving-wheel will move forward into engagement with the reduced portion *l'* of the driving-pulley. The pulley, which is constantly rotating in the direction indicated by the arrow in Fig. 2, will cause the driving-wheel to be turned in a reversed direction, as indicated by the dotted arrow in the same figure. The brake-bar and brake-shoe are ordinarily held by the latch in the position indicated in Fig. 1. When it is desired to apply the brake, the operating-lever is moved first to the position shown in Fig. 1 and then pulled over toward the rear of the carriage, so as to move the rear wheel forward into engagement with the brake-shoe. It will be understood that before the operating-lever can be moved farther to the rear, so as to bring the driving-wheel into engagement with the pulley to drive the carriage backward the brake must be released. This is accomplished by depressing the foot-lever *w* and releasing the latch *v*, when the driving-wheel will push the brake-bar and brake-shoe forward against the force of the spring *u*. When the wheel is again moved backward out of engagement with the driving-pulley, the spring will cause the brake to move into its normal position and the latch *v* will enter its recess to hold the brake-bar in this normal position.

It will be seen that I have provided an ex-

tremely simple means for imparting both forward and rearward motions to the carriage, that the starting of the carriage both forward and back and the stopping are performed by means of a single operating-lever. It will also be understood that by the use of the drop-axles I am enabled to use wheels of much larger diameter and provide a greater clearance between the carriage-body and the ground.

I claim—

1. In an automobile, a frame, a driving-pulley, a driving-wheel, means for moving the driving-wheel away from the driving-pulley and for moving the driving-wheel toward the driving-pulley into engagement therewith, and a spring-pressed movable brake in the frame located in the path of movement of the driving-wheel.

2. In an automobile, a frame, a driving-pulley, a driving-wheel, means for moving the driving-wheel toward and away from the driving-pulley, a movable brake in the frame located in the path of movement of the wheel, and means for holding the brake against movement.

3. In an automobile, a frame, a movable brake in the frame, means for holding the brake against movement, a driving-wheel movable into engagement with the brake, means for releasing the brake, and means for returning the brake to normal position when released.

BYRON B. SWITZER.
